UNITED STATES PATENT OFFICE.

WILLIAM MILTON BROWN, OF JOHNSTOWN, PENNSYLVANIA.

TONGS.

1,111,561.

Specification of Letters Patent. Patented Sept. 22, 1914.

Application filed June 29, 1914. Serial No. 847,893.

To all whom it may concern:

Be it known that I, WILLIAM MILTON BROWN, a citizen of the United States, residing at Johnstown, in the county of Cambria and State of Pennsylvania, have invented a new and useful Tong, of which the following is a specification.

My invention relates to the construction of tongs, and more particularly to tongs used in handling the crucibles employed in making crucible steel. Such crucibles, which are made of clay or plumbago, become softened when subjected to the intense heat of the crucible furnace, so as to be easily crushed or distorted when gripped or clamped by the jaws of the tongs ordinarily employed in handling the heated crucibles.

One object of my invention is to provide tongs of novel construction having improved means for engaging with and grasping the crucibles in the handling thereof incidental to making and pouring the molten metal, so as to avoid cracking or crushing and prevent distortion of the highly heated crucibles.

Another object of my invention is to provide a tong having improved means whereby handling of the crucible in removing the crucible from the furnace and in pouring the molten metal from the crucible is facilitated.

Still further objects of the invention will appear hereinafter as the invention is more fully described in the specification and pointed out in the appended claims.

Referring to the drawings, forming part of this specification, Figure 1 is a side elevation, partly in section, showing tongs constructed and arranged in accordance with my invention. Fig. 2 is a plan partly in section of the tongs construction shown in Fig. 1. Fig. 3 is a transverse section taken on the line III—III of Fig. 2, showing the construction of the hinge or joint of the tongs and the swivel construction enabling the tongs to be turned or tipped in the crucible pouring operations. Fig. 4 is a side elevation, partly in section, showing a modified and preferred form of tongs constructed and arranged in accordance with this invention. Fig. 5 is a plan, partly in section, of the apparatus shown in Fig. 4. Fig. 6 is a transverse section, taken on the line VI—VI of Fig. 5 showing the construction of the hinge and swivel used on the tongs of Figs. 4 and 5. Fig. 7 is a de-

tail plan showing the tongue and registering groove on the ends of the jaws of the tongs.

In the accompanying drawings, referring to Figs. 1, 2 and 3, the numerals 2 and 3 designate the two jaws of the tongs which are curved, each of the jaws having a rein 4 or 5 formed integrally therewith. The rein 5, which is somewhat longer than the rein 4, is provided on one end with a boss 6 having an opening therein through which a handle 7 extends. A link 8 movably secured on the reins, forms a keeper which is employed to hold the tongs in closed position in gripping a crucible. Each of the jaws 2 and 3 of the tongs have outwardly bent portions 9 on the ends thereof, which meet when the tongs are closed and form stops preventing pinching or gripping of the crucibles, so as to in this way avoid crushing or distortion of the crucibles when grasped by the tongs. The jaws 2 and 3 of the tongs are also provided with upwardly extending fingers 10 and downwardly extending fingers 11, these fingers being curved to substantially the contour of the outside of the crucible 12, the outline of which is indicated by dotted lines in Fig. 1. The reins 4 and 5 of the tongs have flattened portions at a point adjacent to where they are joined to the jaws, which cross, and a pivot pin 13 extends through registering openings in the flattened portions of the reins to form the pin for the hinge joint of the tongs. The ends of the pivot pin 13 extend through an annular swivel ring 14 and a head 15 is provided on each end of the pivot pin 13 to secure the ring in position on the tong reins. Fillers 16, 16, are positioned within the ring, one on each side of the reins, through which the pivot pin extends, to prevent movement of the reins lengthwise of the pivot pin 13 without interfering with the opening and closing movement of the jaws 2 and 3 of the tongs. The swivel ring 14 is rotatably mounted within a trunnion ring 17 which has trunnions 18, 18, thereon, these trunnions being secured to rotate in the eyes 19 of the link 20 by which the tongs are suspended by a chain or other flexible connection from a crane, overhead trolley, or like device. The trunnion ring has a cylindrical opening therethrough and the inner surface of this ring 17 is provided with a peripheral groove or depression 21. Out-

wardly extending grooves or depressions 22 are also provided in the trunnion ring, at diametrically opposite points, as is best shown in Figs. 2 and 3, to enable the heads 15 on the pivot pin to enter the groove 21.

In assembling the parts of the tongs of Figs. 1, 2 and 3, the jaws 2 and 3 are pivoted together by means of the pivot pin 13 extending through the holes in the reins 4 and 5, the fillers 16 being placed in position within the swivel ring 14 and the heads 15 then formed on the ends of the pivot pin. The trunnion ring 17 with the link 20 formed in place on the trunnions thereon, is then placed in position, the tongs and swivel ring being turned or rotated at such time so that the heads 15 of the pivot pin 13 will enter the parallel grooves 22 extending to the side of the trunnion ring 17. The tongs and swivel ring are then turned axially, the heads of the pivot pin 13 being then located in the peripheral groove 21 in the inner surface of the trunnion ring 17 so as to prevent displacement of the tongs lengthwise with respect to the trunnion ring, while permitting rotation on an axis parallel with the length of the jaws and the tong reins.

In the preferred construction shown in Figs. 4, 5, 6 and 7 the tongs have curved jaws 2' and 3' which are connected to the reins 4', 5', by bent portions 4'', 5'', of the reins so as to bring the center of gravity of the filled ladle 12' somewhat lower with respect to the axis of rotation of the tongs 35 and swivel ring 14' in the trunnion ring 17' and in this way lessen and prevent the liability of accidentally overturning a crucible filled with molten metal. The jaws 2', 3', have upwardly extending fingers 10' and 40 downwardly extending fingers 11' and the reins 4', 5', are hinged together with a pivot pin 13'. A tongue 23 and registering recess 24 at the outer end of the jaws 2', 3', serve to limit the extent of closing movement of the 45 jaws and to interlock the jaws when the jaws are in closed position. The rein 5' is longer than the rein 4' and is provided with a boss 6' and handle 7' which extends through and is fastened in the opening therein, and a link 8' is employed on the ends of the reins to hold the jaws in closed position in the same manner as in the construction of Figs. 1, 2 and 3.

In the construction shown in Figs. 4, 5 and 6 the trunnion ring 17' is secured to the link 20' by means of trunnion bolts 18', 18'', which have threaded ends screwed into internally threaded openings at diametrically opposite points on the trunnion ring 17'. The swivel ring 14' is inserted in the trunnion ring and the heads 15' of the pivot pin 13 are in the peripheral groove 21' in the inner surface of the trunnion ring 17' in the same manner as in the other figures. In the 65 construction of Figs. 4, 5 and 6 however, the

swivel ring 14' is held in place in the swivel ring by means of the flanged plate 25 which is fastened by the tap bolts 26 to the filler plates 16', 16'.

In using my improved tongs shown in Figs. 1, 2 and 3, the jaws are opened by means of the reins 4 and 5, sufficiently to admit the crucible. The jaws 2 and 3 are then closed and the keeper 8 is then positioned on the reins 4 and 5, to fasten the jaws 2 and 3 in closed position around the crucible, the stops 9 then being in engagement so as to prevent crushing pressure on the crucible 12. The curved fingers 10 and 11 on the jaws of the tongs loosely engage with the curved surface of the heated crucible to prevent removal or displacement of the crucible when the jaws are in closed position. The crucible is then lifted through the medium of the reins and transported on the trolley or crane from which the tongs are suspended to the pouring station. The tongs and crucible are then rotated axially relative to the swivel ring and trunnion rings to tip or tilt the crucible 12 so as to pour the molten metal from the crucible, the handle 7 forming a convenient means for this turning movement. After the crucible is emptied the tongs are employed to move the empty crucible to the place of disposal, and when disengaged from the crucible the tongs are in readiness to repeat the above described operations.

In handling crucibles with tongs constructed as shown in Figs. 4, 5, 6 and 7, the operations will be as has just been described.

The advantages of my invention will be apparent to those skilled in the art. The provision of the stops on the ends of the jaws of the tongs prevents gripping of the crucibles and the possibility of crushing which would result therefrom. The curved fingers projecting from opposite sides of the jaws loosely engage with and retain the crucible in place while preventing removal or dislodgment thereof while the tongs jaws are closed. By having the jaws of the tongs and the rear end of the reins extending lengthwise parallel in different planes the liability of overturning the crucibles is lessened and prevented. The novel means for suspending the crucible tongs permits lifting of the crucible by the tongs and the turning movement of the crucible necessary in pouring. The apparatus is simple and avoids the necessity of frequent repairs.

Modifications in the construction and arrangement of the parts may be made without departing from my invention as defined in the appended claims.

I claim:

1. A tongs comprising curved jaws having reins, a pivot pin connecting the jaws, said reins having bent portions connecting

the jaws with lengthwise parallel portions of the reins, lugs on said jaws to limit the closing movement thereof and a plurality of oppositely extending fingers on the jaws 5 arranged to loosely engage and maintain crucibles between said jaws when the jaws are in closed position.

2. A tong comprising pivoted jaws having reins, a pivot pin therefor, a swivel ring 10 through which the pivot pin extends, a trunnion ring in which said swivel ring is rotatably mounted, means for preventing relative axial movement of the swivel ring and trunnion ring, and a swivel link on 15 which the trunnion ring is mounted.

3. A tong comprising pivoted jaws having reins, a pivot pin therefor, said reins having bent portions between the curved 20 jaws and the pivot pin to connect the jaws and lengthwise parallel portions of the reins, a swivel ring through which the pivot pin extends, a trunnion ring in which said

swivel ring is rotatably mounted, means for preventing relative axial movement of the swivel ring and trunnion ring, and a swivel 25 link on which the trunnion ring is mounted.

4. A tong comprising pivoted jaws having reins, a pivot pin therefor, a swivel ring 30 through which the pivot pin extends, heads on opposite ends of said pivot pin, a trunnion ring in which said swivel ring is rotatably mounted, said trunnion ring having a peripheral groove on the inner surface thereof to receive the heads of said pivot pin and thereby retain the trunnion ring in 35 place on the swivel ring, and a swivel link on which the trunnion ring is fastened.

In testimony whereof, I have hereunto set my hand.

WILLIAM MILTON BROWN.
